FIG. 5.

FIG. 6.

FIG. 7.

John H. Hammann,

By

Clifton C. Callowell
Attorney

UNITED STATES PATENT OFFICE.

JOHN H. HAMMANN, OF TOTTENVILLE, NEW YORK, ASSIGNOR TO THE S. S. WHITE DENTAL MANUFACTURING COMPANY, A CORPORATION OF PENNSYLVANIA.

TOOTH HOLDER.

Application filed August 21, 1922. Serial No. 583,120.

To all whom it may concern:

Be it known that I, JOHN H. HAMMANN, a citizen of the United States, and a resident of Tottenville, in the county of Richmond, 5 State of New York, have invented certain new and useful Improvements in Tooth Holders, of which the following is a specification, reference being had to the accompanying drawings.

10 My invention relates particularly to that class of devices upon which a tooth may be supported, and employed by dentists in determining, by comparison, the particular shade, form and size of artificial stock teeth 15 or facings that may best be substituted for the natural teeth of the patient so as to most nearly conform to the teeth of the patient with which said stock teeth or facings are to be associated, and is especially 20 directed to means for detachably engaging the teeth to be supported thereby.

The principal object of my invention is 25 to provide a tooth-holder with which different teeth may readily be detachably engaged and be thrust thereby into the mouth of the patient in such position as to be most conveniently compared with the teeth in the patient's mouth, to determine the form, size and shade of stock teeth or facings that 30 are best adapted to be associated therewith.

Other objects of my invention are to provide a tooth-holder having means for detachably engaging an artificial tooth and permitting it to be rotated thereon into dif- 35 ferent positions with respect thereto, and to so engage said tooth as to cause it to be tipped, when thrust thereon to the limit of its lineal movement, which in effect tends to secure it against accidental displacement.

40 My invention comprehends a tooth-holder having a yielding support for artificial teeth, whereby the tooth supported thereon is frictionally engaged to prevent its accidental displacement.

45 My invention further includes a tooth-holder which is of such simplified construction as to be economically produced, and which may be readily sterilized.

Specifically stated, the form of my invention, as hereinafter described, comprises a tooth-holder having a handle whose forward end is extended obliquely, and provided with an integral spring tang punched therefrom and carrying a headed projection ar- 50 ranged to engage the undercut walls of an

artificial tooth, and thereby frictionally engage the lingual surface of said tooth with the obliquely directed free end of said handle.

My invention also includes all of the various novel features of construction and arrangement as hereinafter more definitely specified.

In the accompanying drawings, Figure 1 is a perspective view of a tooth-holder constructed in accordance with my invention; Fig. 2 is a front elevational view of the tooth-holder shown in Fig. 1; Fig. 3 is a view similar to Fig. 2 but showing a tooth facing operatively mounted thereon; Fig. 4 is a longitudinal sectional view of said tooth-holder and the tooth facing taken on the line 4—4 in Fig. 3; Fig. 5 is a longitudinal sectional view of a modified form of tooth-holder; Fig. 6 is a longitudinal sectional view of another modified form of tooth-holder; and Fig. 7 is a fragmentary sectional view showing how the tooth is applied to the tooth-holder.

In the form of my invention shown in 80 Figs. 1—4 inclusive, the handle 1 having its forward end extended obliquely to provide the seat 2 for the tooth facing 3, has the spring tang 5 punched outwardly from said seat and provided with the projection or 85 pin 6, having the head 7 extended through the opening 9 which is formed in said seat by punching the spring tang therefrom.

The opening 9 forms the lateral bars 10 of the seat 2, upon which the lingual surface 90 of the tooth facing 3 is arranged to rest, and against which it is frictionally held by the spring tang 5 whose headed pin 6 is arranged to extend through the slot 12 in the tooth facing 3, while its head 7 engages the 95 undercut walls 13 of the recess 15 in said tooth facing 3. In this form of my invention, the spring tang 5 is punched clear of the plane of the obliquely extended end of the handle forming the seat 2, and extends 100 offset, substantially parallel therewith, preferably joining the handle by an ogee curve as best shown at 16 in Figs. 4 and 7, and while the headed pin or projection 6 is shown as being riveted at 17 to said spring 105 tang, it is obvious that it might be otherwise connected in any convenient and well-known manner.

In the form of my invention shown in Fig. 5, the handle 19 has its forward end 110

extended obliquely to form the seat 20, and has the spring tang 21 punched therefrom and provided with the headed pin or projection 22 arranged to frictionally engage 5 the tooth facing 23 with the seat 20. In this form of my invention, the tang 21 does not have the ogee curve, such as shown in Fig. 4, but merges from the seat, inclining backwardly therefrom toward its free end.

10 In the form of my invention shown in Fig. 6, the handle 25 has its forward end extended obliquely to form the seat 26, against which the tooth facing 27 is held by the headed pin 28 which is carried by the spring 15 tang 29. In this form of my invention the spring tang 29 may be separately formed and secured by riveting, welding or in any suitable manner to the obliquely extended end of the handle 25. Said headed pin 28, 20 which is carried by said spring tang 29, extends through a suitably provided opening 30 in the seat 26, to engage said tooth facing 27 as shown.

As best shown in Fig. 7, the tooth facing, 25 which is provided with a ridge-lap 31, shut surface 32 and a bite bevel 33, is conveniently engaged with the seat of the tooth-holder, by riding the shut surface 32 on the parallel lateral bars 10 of the seat 2, until the pin or 30 projection 6 reaches the end of the slot 12. The engagement of the pin or projection 6 with the end of the slot 12 causes said tooth facing to teeter on the angle formed by the intersection of the shut surface 32 and bite 35 bevel 33 and to assume the position shown in Fig. 4, wherein the bite bevel 33 engages the parallel bars 10 forming the seat 2, and the undercut walls 13 of the tooth facing assume the plane of the flat under surface 40 of the head 7, whereby said tooth facing is in effect snapped into its operative position and yieldingly retained against accidental displacement.

It will be noted that while I have shown 45 the tooth held with its incisal edge 35 disposed toward the handle 1, it may be rotated on the headed pin 6, so that the incisal edge 35 will be oppositely disposed away from the handle, as shown in dotted lines in Fig. 50 3, or it may be disposed obliquely toward the left, as shown by the dash lines in Fig. 3, or it may be disposed toward the right of said handle, as shown in dot and dash lines in said figure, or it may assume any position 55 within the circle of rotation.

It will be obvious that the tooth facing thus held by the tooth-holder may be conveniently thrust into the patient's mouth in

close proximity to the teeth therein, so that 60 accurate comparison may be made as to the color or shade, the size and the form of tooth best adapted to be associated with the teeth in the patient's mouth.

I do not desire to limit my invention to the precise details of construction and arrangement as herein set forth, as it is obvious that various modifications may be made therein without departing from the essential features of my invention as defined in the appended claims. 70

Having thus described my invention, I claim:

1. A device of the class described, comprising a handle having its forward end extended obliquely to provide a seat for an 75 artificial tooth, and having a spring tang punched therefrom and provided with means to detachably engage said tooth in frictional contact with said seat.

2. A device of the class described, comprising a handle affording a seat for an artificial tooth, and having a spring tang extended from the plane of said seat arranged to rotatably support said tooth in frictional engagement with said seat. 80 85

3. A device of the class described, comprising a handle having its forward end extended obliquely to afford a seat for an artificial tooth, and provided with a spring tang extended from the plane of said seat having 90 a headed projection arranged to detachably engage said tooth with said seat in rotatable relation therewith.

4. A device of the class described, comprising a handle having its forward end extended obliquely to provide a seat for an artificial tooth, and having a spring tang having a headed projection punched from said seat and affording an opening therein through which said headed projection on 100 said tang may extend to yieldingly engage said tooth with said seat.

5. A device of the class described, comprising a handle having a seat for an artificial tooth, said seat being provided with 105 an aperture, and a spring tang having means extended through said aperture and arranged to yieldingly engage said artificial tooth with said seat, by a pulling action.

In witness whereof, I have hereunto set 110 my hand this 31st day of July, A. D., 1922.

JOHN H. HAMMANN.
